HIS ATTORNEY

UNITED STATES PATENT OFFICE.

GRANVILLE A. HUMASON, OF HOUSTON, TEXAS.

PUMP-PISTON.

1,327,914.

Specification of Letters Patent. Patented Jan. 13, 1920.

Application filed October 11, 1919. Serial No. 330,058.

To all whom it may concern:

Be it known that I, GRANVILLE A. HUMASON, a citizen of the United States, residing at Houston, Harris county, Texas, have invented a certain new and useful Improvement 5 in Pump-Pistons, of which the following is a full, clear, and exact description, such as will enable others skilled in the art to which it appertains to make and use the 10 same.

My invention relates to an improvement in expanding cups or rings to be used in connection with a reciprocating pump piston whereby the wear incident to the operation 15 of the pump may be taken up without the removal of the operating parts from the well.

In the operation of deep well pumps, and especially in pumps employed in the pumping 20 of oil or water mixed with sand or sediment occasioning rapid wear in the piston and working barrel, it is desirable that the wear may be remedied by the expansion of the parts of the piston so that the tight fit 25 between the piston and working barrel may be maintained without the necessity of removing the parts from the well. The expansion means used on the piston will be shown also to be adaptable for use in locking 30 the foot valve in the lower end of the working barrel so that it may be removed when desired.

The object of my invention is to provide a novel form of expansion means adapted 35 to be expanded by the rotation of the sucker rod connected therewith.

Referring to the drawings forming a part 40 of this specification, and wherein like numerals of reference are applied to like parts throughout the several views, Figure 1 is a central longitudinal section through the lower end of the working barrel of a pump showing the use of my invention both upon the piston and the foot valve of the pump; Fig. 2 is a transverse section on the plane 45 2-2 of Fig. 1; Fig. 3 is a similar section on the plane 3-3 of Fig. 1; Fig. 4 is a plan view of one of the metallic disks used in connection with my expansion means.

In the sectional view shown in Fig. 1, I have illustrated the lower end of an ordinary working barrel A having therein a foot valve B and a reciprocating piston C. The working barrel A is shown as connected 55 at its lower end to a wash pipe 5 by means

of a coupling 6. This coupling is provided with an inwardly extending diaphragm or flange 7 having a central opening or channel 8 therein for the passage of the fluid from the wash pipe 5 into the lower end of the working barrel. At each side of this central passage 8 the diaphragm has a rectangular recess or groove 9 into which a downwardly projecting flange 10 upon the foot valve B is adapted to seat. The foot valve operates after the manner of the usual foot valve, having a central pipe or passageway 11 on the upper end of which is attached a valve cage 12, providing in the lower end thereof a seat 13 for the upwardly opening ball valve 14. At the lower end of the pipe 11 of the foot valve is a nut 15 having on its lower face the projecting flange 10 previously described. A somewhat similar nut 16 is provided at the upper end of the pipe 11 and between these two nuts are adapted to be clamped a plurality of expansion devices.

The expansion means used in connection with my foot valve is identical with the means used in the plunger to be later described. It comprises two compressible composition disks or cups 17 and 18. These cups being reinforced on their inner adjacent faces by resilient metallic disks 19 which are slit radially at 20 adjacent their outer edges. These disks have a flat face 21 bearing against the expanding disk toward the central passage 11 and are bowed or curved toward each other at their outer margins so that they will contact along the said margins 22. These metallic disks press against the expansion cups so as to force the outer inturned edges thereof outwardly into contact with the working barrel. The upper of the two expansion cups is reinforced on the side opposite the metallic disk by the nut 16, which has its lower face concaved for that purpose. The lower disk is reinforced by a saucer-shaped metallic disk 23, the lower face of which is adapted to bear against a similar metallic disk 24 bowed in the opposite direction and acting to reinforce the upper face of the expansion cup 25 adjacent thereto. The lower set of expansion cups 25 and 26 are constructed in the same way as the sets 17 and 18 previously described, having the two inner metallic washers 19 and 21 acting to force the expansion cups outwardly against the 110

working barrel and the lower face of the disk 26 reinforced by the upper concaved surface of the nut 15.

The nut 15 is provided with a locking device which acts to prevent the unscrewing of the nut from the piston. This locking device comprises a radial opening 27 in which is seated a ratchet or latching means adapted to bear against the inner pipe 11. The latching means comprises an inner head 28 beveled at its inner face at 29 and having an outer stem 30 about which is seated a helical spring 31, said spring seating at its outer end upon a threaded plug 32, which acts to close the outer end of the opening. The spring 31 thus acts to force the latch 28 resiliently inward against the pipe. The pipe at this point is threaded to receive the nut and is provided with longitudinal grooves 33, which extend for a short distance between the ends of the threaded portions to receive the beveled end 29 of the latch. These grooves are provided with a radial side 34 and another side 35 at approximately right angles thereto. Thus by reference particularly to Fig. 3 it will be noted that the rotation of the nut in a right hand direction will be accommodated by the sliding of the latch from one notch to another along the beveled face 35 of the notch, but when it is desired to unscrew the nut by a rotation in a counter-clockwise direction, the side of the latch will contact with the radial side 34 of the groove and prevent its movement. The grooves 33 do not extend the full length of the threaded portion to prevent the passage of liquid past the nut. There are, as will be noted, full threads unmutilated both above and below the grooves which will act as a liquid seal to prevent leakage around the nut.

The upper end of the cage 12 is threaded at 36 for coupling with the sucker rod or other pipe and is squared at the extreme upper end at 37 for the attachment of a wrench or other rotating means.

In the assembling of this foot valve, the parts are placed together, as shown in Fig. 1, with the lower nut 15 holding the expansion means loosely therebetween. A wrench attachment at the lower end of the sucker rod is placed over the squared upper end 37 of the foot valve and the assembled device is forced downwardly to the lower end of the working barrel until the flange 10 seats within the groove 9 of the lower coupling. This will act to hold the nut 15 against rotation. If the sucker rod is then rotated in a right hand direction it will serve to rotate the upper nut 16 and the attached central pipe 11 downwardly into the nut, thus compressing the expansion means between the two nuts. The pressure of the metallic disks 19 and 21 together will cause the outer con-

tacting ends 22 to be forced outwardly thus compressing the inwardly extending ends of the expansion cups 17 and 18 against the working barrel sufficiently to make a fluid tight closure. If at a subsequent time the closure is found to be loose, the wrench attachment may again be used to still further compress the expansion cups and to tighten the closure. If it is desired to remove the foot valve from the well it may be loosened by rotation in the opposite direction and a threaded coupling may be attached to the threaded upper end 26 and the foot valve may thus be removed from the well.

The construction of my reciprocating piston is very closely identical with that of the foot valve just described. There is a central pipe 38 providing a passage for the fluid therethrough, a valve cage 39 at the upper end and a sucker rod 40 connected to said valve cage by means of a coupling 41. Upper and lower nuts 42 and 43 act to compress between the same a plurality of pairs of expansion composition disks 44 and 45, which are adapted to be compressed between the two nuts and to be forced outwardly against the sides of the working barrel by resilient metallic disks 46 and 47, as previously described, in relation to the foot valve. The lower nut 43 is provided with a locking means 48 similar in construction to the one described at the lower end of the foot valve. This nut is constructed with a squared opening 49 centrally thereof, thus forming a seat adapted to receive the squared upper end 37 of the foot valve B. Thus when it is desired to compress the expansion disks between the nuts 42 and 43, the piston is lowered so that it is seated upon the upper end 37 of the foot valve and then is rotated to tighten the nut 43 upon the pipe 38, compressing the expansion means so as to force the inturned ends of the expansion cups outwardly against the working barrel to cause a tight closure between the piston and the walls of the working barrel.

Thus whenever it is noted that there is a leakage about the piston due to a wearing of the operating parts, the piston may be lowered into contact with the foot valve, and the expansion cups compressed so as to tighten the closure between the piston and the working barrel, and the operation of the pump may again proceed as before. By the provision of the locking means upon the nuts 15 and 43 it will be impossible for the nuts to become loosened from their proper position but it will, however, enable the tightening up of these parts when such operation is desired.

Having thus described my invention, the operation and advantages of which will be clear without further description, what I

claim as new and desire to protect by Letters Patent is:

1. In a pump, a working barrel, a piston reciprocable therein, expansion means on said piston, said means comprising pairs of cups with their outer ends turned toward each other, resilient metallic disks between said cups, said disks pressing against the in-turned ends of said cups whereby the compression of said disks will force said cups against said working barrel.

2. In a pump, a working barrel, a piston reciprocable therein, nuts at the upper and lower ends of said piston, expansion means between said nuts, said expansion means comprising a series of cups having their outer ends bearing against said working barrel and their concave faces toward each other, resilient disks between said cups, said disks having their outer edges bearing against the outer edges of said cups, whereby the tightening of one of said nuts will force the cups outwardly against said working barrel.

3. In a pump, a working barrel, a piston reciprocable therein, pairs of expansion members thereon comprising flexible cups, saucer-shaped metallic disks between said cups and acting when compressed to force said cups against said working barrel.

4. In a pump, a working barrel, a piston reciprocable therein, expansion means thereon comprising a flexible cup, said cup being held resiliently between saucer shaped metallic disks, the inner of said disks bearing against the outer edge of said cup and means to compress said cups and said disks to force said cups outwardly against said working barrel.

5. In a pump, a working barrel, a piston reciprocable therein, expansion means on said piston comprising flexible cups in pairs

with the concaved faces toward each other, saucer-shaped metallic disks bearing against said cups, said disks being slit radially along the outer edge thereof, said outer edges bearing against the edge of the adjacent cup and means to compress said cups and said disks to force said cups against said working barrel.

6. In a pump, a working barrel, a foot valve in the lower end thereof, a piston reciprocable in said working barrel, pairs of expansion cups on said piston, resilient saucer shaped metallic disks pressing against said cups on both sides thereof, and means to force said cups toward each other, causing the concaved faces of each pair of disks to contact and expand the cups against the working barrel.

7. In a pump, a working barrel, a foot valve therein, means to lock said foot valve in said working barrel comprising flexible cups, disks bearing on said cups and adapted to expand the same, a piston reciprocable in said working barrel, expanding cups on said piston, nuts at the upper and lower ends of said piston adapted to compress said cups to expand the same by the threading of said piston downwardly relative to said lower nut.

8. In a pump, a working barrel, a foot valve therein, a squared upper nipple thereon, a piston in said working barrel, nuts on the upper and lower ends thereof, compressible cups between said nuts, the lower of said nuts having a recess to receive said nipple whereby the rotation of said piston will compress said disks and expand the same.

In testimony whereof, I hereunto affix my signature, this the 8th day of October, A. D., 1919.

GRANVILLE A. HUMASON.
